CARBURETING IN INTERNAL COMBUSTION ENGINES

Eugen Ludwig Müller, Berlin, Germany

Application March 18, 1936, Serial No. 69,582
In Germany March 30, 1935

1 Claim. (Cl. 261—95)

There is a type of internal combustion engine working with compression of the mixture and with electric ignition in which the proportion of fuel is determined by a pump driven by the engine. The fuel may be introduced into the induction pipe or into the cylinders through nozzles or fuel valves, which atomize the fuel very finely, when a very high pumping pressure is used.

10 According to the invention such nozzles or valves are replaced by porous bodies located in the air supply pipe, and the fuel is forced through these in a very finely divided condition, and is exposed to the passing air over a large 15 surface.

By this means extremely fine subdivision of the fuel is obtained with quite small pumping pressures, and formation of large drops is prevented. As is well known the rate of delivery 20 of fuel during a stroke of the pump cannot be exactly adapted to the conditions of suction of the engine at different speeds and loads; so that when nozzles are used it is impossible in some conditions of working to avoid drip of fuel after 25 injection, or formation of drops prior to the suction stroke. The porous bodies which the invention substitutes for nozzles exert a strong braking action on the very fine particles of fuel forced through them, so that dripping of the 30 fuel is prevented; and because of its bibulous properties the bodies serve as an equalising reservoir between successive suction strokes of the engine.

This equalising action also makes it possible 35 to use a single injector for several cylinders instead of one for each cylinder. To make this clear Figures 2, 3 and 4 show in full lines the air demand of an engine plotted against its crank angle, and by broken dotted lines the fuel 40 delivery. Figure 2 refers to a four-stroke single cylinder engine with a single cylinder fuel pump driven by the cam shaft. If the pump piston is actuated by a cam of suitable form the fuel delivery can be adapted to the air demand of 45 the engine in such fashion that the mixture ratio of air to fuel is approximately constant throughout the suction stroke. The broken line shows this condition. If a pump with swash-plate drive is employed for the sake of conveniently regulating the fuel delivery by varying the stroke of 50 the pump, the delivery of the pump extends over 180° of the pump or cam shaft revolution as shown by the dotted line of Figure 2, i. e., over a complete revolution of the engine shaft. Thus 55 the period of injection is about twice as long as

the suction stroke of the engine. With the usual nozzles this would lead to impossible conditions; but if a filter element is used it assumes an average condition of saturation, retains fuel when the air column is at rest, and delivers it only 5 to air which is traveling past it. Formation of drops is avoided; the fuel is admixed with the air in the form of a fine cool cloud.

Figure 3 shows the conditions for a four cylinder four-stroke engine, with a swash-plate 10 driven two-cylinder pump driven from the crank shaft.

Figure 4 shows the diagrams for a four-cylinder four-stroke engine with a four-cylinder swash-plate fuel pump driven from the cam 15 shaft. The broken lines show the delivery by the several cylinders of the fuel pump, the dotted line the total delivery of the fuel pump.

In four-stroke engines with more than four cylinders and two-stroke engines with more than 20 two cylinders, the suction strokes of the several pistons will overlap, so that there is a continuous demand for fuel.

To obtain even delivery to the several cylinders the fuel pump and its actuating mechanism should be such that the fuel delivery is in 25 phase with the air suction.

Figure 1 shows in section an example of construction of the invention.

The housing of the apparatus is built of two 30 parts 1 and 2. The air supply pipe 3 may either draw from the atmosphere or be fed by a super-charger. Between the upper and lower parts 1, 2 of the housing is an annular filter element 4. The fuel delivered by the controlled fuel pump 35 is led through a tube 5 to the narrow annular space 6 between the filter element and the housing. Packing 7 and 8 prevents leakage of fuel directly into the interior of the housing. Screws 9 fasten the parts 1, 2 and the filter element 40 between them to form a rigid block.

Within the casing a stream-lined throttle cone 10 is arranged for vertical movement, guided by webs 11 in the lower part of the casing and a stem 12 in the upper part. Downward movement 45 of the cone is limited by nuts 13, 14 by the aid of which the width of the conical annular space between the throttle cone 10 and the filter element 4 can be exactly set, and so the proper throttle opening for satisfactory idling determined. It is of great importance for satisfactory 50 idling that the air required shall flow at high speed over the filter element and contact with the whole surface of the element. It is a feature of the invention that the filter element itself 55

forms part of the throttle, for that not only secures good contact between air and fuel as just stated, but also by eliminating the throttle valve usual with common carburetors eliminates eddy formation in the mixture. From the lower part 2 of the housing the mixture is led to the engine.

Upward movement of the throttle cone is limited by the abutment 15 which strikes the inner wall of the part 1 as shown in broken lines in the drawing. At the upper end of the stem 12 is a pivot pin 16 with which engages a throttle regulating rod not shown in the drawing.

In order that the force requisite to move the throttle cone may not be too great, particularly in passing from idling to load position, a part of the air suction and drag exerted on the throttle may be balanced by compensating springs suitably arranged upon the operating rod, or by a pneumatic balancer. In such a balancer the difference of pressure on the two sides of the throttle may act upon a diaphragm, or, as shown in the example illustrated, through a tube 17 upon a piston 18, which is connected with the pin 16 through linkwork 19, 20, 21, 22, and so opposes to the downward force exerted on the cone 10 (which is also exerted on the piston 18) an upward force on the pin 16. In the drawing the cylinder 23 is shown open to the atmosphere above the piston 18 through the orifice 24. If supercharging is employed it may be desirable to connect the upper end of the cylinder 23 with the upper part 1 of the housing of the apparatus. When the throttle is fully open the linkwork 19, 20, 21 and the pin 16 take the position shown in broken lines and the piston 18 is at the bottom of the cylinder 23.

Any form of filter element, whether a porous block or a woven fabric, may be employed, subject, in the latter case, to the material being stretched upon a hollow vessel or on a suitable skeleton.

A block filter element, or the frame of a fabric filter may be cemented or soldered into the carburetor housing.

The porosity and the fineness of the pores of the filter are not of great importance, since the proper proportion of fuel in relation to the air is determined by the fuel pump; for the same reason the device will continue to work even though the filter element be largely blocked up, and renewal of the element will be necessary only at long intervals.

Fuel pumps of moderate output pressure (say about 10 atmospheres) may be employed; and the output pressure may in course of time fall off greatly through wear without causing failure since a pressure of about two atmospheres is ample for the operation of the device.

It is to be expected that the fine subdivision of the fuel without heating will enable engines fitted with the invention to employ considerably heavier fuels than would otherwise be possible.

I claim:

A method of forming a combustible mixture for internal combustion engines which comprises the steps of forcing the fuel under pressure through a porous body to reduce the fuel into finely divided particles in its forced passage through the porous body, and passing air past the porous body to take up and mix with the fuel and form the combustible mixture.
